STOVE

Charles G. Schott, St. Louis, Mo.

Application October 10, 1929. Serial No. 398,657

6 Claims. (Cl. 126—69)

This invention relates to improvements in stoves, and particularly to stoves of the class known as magazine heaters, or base burners.

An object of the present invention is an improved provision for retarding the passage of smoke and flue gases, sufficiently to insure efficient absorption of surplus heat, within the heater, prior to their exit in the chimney outlet. This object may be otherwise stated as the attainment of an increased length of flue gas passage, between the firebox and flue, whereby a greater area of heat-absorbing passage is provided, with a view of reducing the usual heat-loss incident to flue gases and unburned volatile or gaseous combustibles.

A further object is to provide simple and effective means for inducing a current of excess air into the interior of the firebox above the grate, and to provide means for preheating the air prior to its admission to the unburned combustible.

A still further object is to provide a jacketed heater, with heating passages extending, not only around the lateral heating portions of the stove, but providing radiation over the entire bottom area of the heater, in a manner to counteract floor drafts and the like.

A still further object is to provide an improved flue clean out, which is easily and readily accessible from the front of the heater, and which, in addition, serves as the means, noted in the object above, for circulating hot flue gases over the entire base of the heater.

An additional object is to provide an improved heater which is simple and durable in construction, and which materially reduces the cost of assembly and maintenance.

Further objects and advantages will appear from the following detailed description of parts and the accompanying drawing, in which: Fig. 1 is a sectional elevation of a preferred form of stove embodying certain of the present improvements; Fig. 2 is a sectional view taken along line 2—2 in Fig. 1; and Fig. 3 is a sectional view taken along line 3—3 in Fig. 1.

It will, of course, be understood that the present detailed description of parts and the accompanying drawing relate to a single preferred executional embodiment of the invention, and that substantial changes may be made in the described arrangement and construction of parts without departing from the spirit and full intended scope of the disclosure, as defined by the appended claims.

Referring by numerals to the drawing, 10

designates, generally, a fire box or pot arranged to be used, in the present construction, in a jacketed form of heater. This box includes, by preference, a plurality of sectional liners 11, 12 and 13, which, when interlocked along their edges 14, in any suitable manner, as by flanges (not shown), constitute the inner fire box or liner of the stove. In the presently preferred example, four of such sections form the complete inner liner, although it will be apparent that with minor changes any desired number of sections may be used. By this provision, ease and simplicity of assembly and replacement is obtained, due to the fact that any one or all of the sections may be readily removed or replaced as may be necessary. The fire box is removably supported on a member 15, which also serves as a support for a movable shaker grate 16. Each liner (such as 11 and 12) is, by preference, tapered upwardly and outwardly from the member 15, to form a flange portion 17, and is provided on or near this flange portion, with a plurality of elongated openings 18 for a purpose hereinafter appearing.

A firing door 19 is hingedly secured to a front closure member 20, which, with the sections 11, 12 and 13, provides a continuous fire lining for the heater. An ash compartment 21 is rigidly secured to the member 15, the sides of the compartment forming a continuation of the inner liners 11 and 12, and the base of the compartment constituting a bottom closure for the fire box 10. This compartment is provided with a removable ash pan 22, which may be withdrawn through an opening 23 for cleaning purposes. The above described assembly is supported, by preference, on lugs 24 which are securely attached to a base 25 for the heater. These lugs are of sufficient length as to provide a broad passage 26 between the bottom of the ash compartment and the base 25, for a purpose hereinafter appearing. It will be understood that the sides and bottom of the ash compartment are, by great preference, imperforate, because of the fact that this structure serves to separate the space just below the fire pot, from the heated air circulating jacket which extends not only around the ash compartment, but across the bottom thereof, to form the double bottom, base-radiating arrangement hereinafter more clearly appearing.

An inner liner or partition 27 is, by preference, spaced from, but in enclosing relation to the fire box 10, to form a heat chamber 28 therebetween. The front portion of the chamber 28 is consti-

tuted by the front closure 20, and the wall portions of the inner liner 27 are, by preference, fitted closely to flange portions 17 of the sectional fire-pot liners, so as to enclose and position the sectional liners in the heating chamber 28. The partition 27 extends from the base 25, to form a seat 29 above the fire box, which is provided with a cover 30 for enclosing the chamber 28 and the fire box 10. By this arrangement the smoke and flue gases from the fire pot are directed through the openings 18 in the liners 11 and 12, and thence into the heat chamber 28. These hot gases are then directed downwardly through the passage 26, in order to heat the base portion 25. It will therefore be seen that the passage 26 forms a continuation, and constitutes a part of, the chamber 28.

An opening 31 is provided in the inner liner 27, near the base 25, and is in communication with a flue back 32 which is attached to and spaced from the liner 27. The flue gases from the chamber 28 and passage 26 normally pass through the opening 31 into the flue back, to be discharged through a stack or outlet opening 33. In the partition 27 and disposed substantially adjacent the opening 33, is provided an opening 34 which is arranged to be closed by a damper 35 pivotally or otherwise suitably secured to the liner 27. This damper may be actuated either to open or close the opening 34, or when the damper is positioned substantially as shown in dotted lines in Fig. 1, it may serve partially or completely to obstruct the gas flow upwardly and along the flue back 32. It will be readily understood that when the damper 35 is positioned as shown in solid outline in Fig. 1, the draft from the stack opening 33 compels the smoke and flue gases in the fire box to traverse a relatively longer path, as indicated by the dotted arrows. This circulation increases the path of travel of the flue gases, by directing the gases downwardly through the chamber 28 and passage 26, and thence outwardly along the flue back 32, to the outlet opening 33. If, however, the damper is positioned as indicated in dotted lines in Fig. 1, the major portion of the smoke and hot gases will be by-passed directly through the opening 34 and out the stack 33, thereby losing valuable quantities of heat which otherwise would be absorbed and radiated. It will be apparent that this last position of the damper is, by preference, used only during starting of the fire, and that the position of the damper may be modified according to the stage of combustion.

Smoke and hot flue gases circulating through the chamber 28 and passage 26 are prevented from admixture with the air flowing beneath the grate and thence into the fire box, by means of a movable clean out door 36. It will be readily understood that any soot or ash particles carried from the fire box 10 into the chamber 28 and the passage along flue back 32, will be deposited for the most part, upon the base 25, and may be removed therefrom through the door 36. Hingedly attached to the front closure assembly of the heater, is an ash door 37 which is, by preference, of such an area as entirely to conceal both the ash compartment and the clean-out door 36. This ash door is provided with an adjustable draft opening 38 to permit air to be drawn through the ash compartment to supply air to the burning fuel in the fire pot.

An outer casing 39 is supported marginally on the base 25. This casing may be of any desired 75 curvilinear section, or may be formed of rectan-

gular section, substantially as shown. The casing is suitably spaced from the heating unit proper to form passages 40, constituting a jacket which entirely surrounds the walls of the heater. The base 25 is provided with circulating-air inlet openings 41, by which atmospheric air first enters the passages 40. The air entering these openings, as indicated by the arrows drawn in full lines, (Fig. 1), is directed into contact with the heated walls of the inner liner and related parts, whence the heated air is discharged into the atmosphere through a perforated cover 42 supported on the casing 39. It will be apparent that the incoming air conducted by the passages 40, is used partially to supply preheated air through the opening 38 to the grate. Suitable doors 43 and 44 are hingedly supported on the outer casing, being positioned substantially in register with the fire door and ash door, respectively, for ready access to the interior of the heater.

In communication with the front passage 40 is a hot blast fitting member 45 which is securely attached to the member 20. This blast member extends inwardly and centrally of the fire pot 10, being provided with a suitable movable damper 46 to regulate the flow of air, through the hot blast fitting, from the passage 40 to the fire pot. This member is adapted to supply excess air to the unburned combustibles in the fire pot prior to their exit through the openings 18 in the liners, in a manner well understood in the art. It will be readily seen that the air supplied to this member is preheated as it proceeds through the passage 40, and thereby promotes the efficiency of fuel combustion within the fire box.

In the preceding description as coordinated with the drawings, it will be seen (Fig. 1) that a dual circulation of fluid currents prevails through the heater, viz., the circulation of flue gases, smoke, including burned and unburned products of combustion, this system being identified by the dotted line arrows. Separate from the flue gas currents, to an extent preventing admixture, is the atmospheric circulation in the jacket, which is traceable by the arrows appearing in full lines.

The entire assembly as above described may be supported on legs or standards 47 of sufficient length to elevate the base 25 substantially above the floor. This elevated positioning of the base permits large volumes of air to be drawn into the passages 40 without creating a distinct floor draft. It will be understood that floor drafts are further minimized by the present, preferred arrangement of heating chamber 28 relative to the fire box, which insures a direct circulation of hot gases about the inner liner and across the entire area of the base 25. This provides a double bottom construction, resulting in base radiation, which materially counteracts floor drafts prevalent in the ordinary types of heaters.

In the preceding description of the parts of the heater constructed according to this invention, it has not been regarded as necessary to set forth in detail the various holding and securing means employed in assembly. For this purpose, flanges or the like, either alone or together with the ordinary stove bolts, may be employed wherever necessary, and as well understood in the art.

The presently described stove is a preferred arrangement embodying certain novel constructional features, among which may be particularly noted the described means of deflecting 150

the hot flue gases downwardly through the chamber 28 and passage 26. This increases the path of travel considerably over the older, prevailing constructions, and thereby sufficiently 5 retards the discharge of these gases to permit ample time for absorption of the heat by the air circulating in the jacket portion of the heater. In the prevailing types of stoves employing direct chimney draft, an unwarranted portion of 10 the heat of combustion is prematurely discharged into the stack. By the present, preferred arrangement, a greater portion of this heat is absorbed in the heater jacket, prior to its discharge into the stack, thereby greatly improving 15 the efficiency of the heater and substantially reducing the amount of fuel used.

The combination of features of construction by which the air passage across the base and internally of the jacket, is utilized as a soot trap 20 and clean out passage, as well as a circulating air channel, is conducive not only to heating efficiency, but to cleanliness of the flue passages and the heater as a whole, particularly when employed for domestic use.

25 I claim as my invention:

1. In a stove, a fire box having an upwardly and outwardly flared upper wall portion, said portion having a peripheral series of radially disposed slots, an imperforate top closure for the 30 fire box adapted to deflect the products of combustion downwardly through said slots, a jacket disposed about, and engaging the flared portion of said fire box, an outer casing enclosing said jacket, said jacket and casing extending to points below the fire box and forming inner and outer 35 separate passages, each extending around the fire box, the inner passage being adapted to receive flue gases through said slots in the fire box, and the outer passage being adapted to permit 40 the flow of air therethrough in a direction opposite to the flow of flue gases through the inner passage.

2. In a stove of circulating type, a base plate having marginal, air inlet openings, a central combustion chamber spaced above said base plate, said chamber having an outwardly flared, upper wall portion, apertured to pass flue gas therethrough, a jacket extending between, and engaging the base plate and flared wall portion 45 of said chamber, said jacket forming a passage substantially surrounding the chamber, adapted to receive flue gas at its upper end and direct such gas downwardly and across the base plate; a casing completely surrounding said jacket and 50 chamber, forming a passage for air to be heated.

3. In a circulating heater, a central combustion chamber including a fire box and ash receiver, the combustion chamber terminating upwardly in an outwardly flared wall portion, said 55 wall portion having a series of peripherally disposed flue gas discharge openings, a tubular

jacket enclosing the combustion chamber, said jacket projecting above the flared portion and below the ash receiver of said chamber, an imperforate closure member for the upper end of said jacket, said jacket forming a passage substantially surrounding the combustion chamber and communicating therewith through said flue gas discharge openings, a casing spaced from, and surrounding said jacket, said casing forming a passage for combustion and circulating air, and a base plate disposed at the lower ends of said jacket and casing.

4. In an air circulating heater, a central combustion chamber including a fire pot and ash compartment, a tubular jacket surrounding said combustion chamber and extending a substantial distance below said ash compartment, said jacket forming an annular smoke passage about the combustion chamber, communicating with the upper portion of said chamber; a base plate at the lower end of said jacket forming a horizontal passage below the ash compartment, the horizontal passage being in direct communication with said annular smoke passage, said jacket having an opening for access to the ash compartment and horizontal passage, a closure member for said opening, and an outer casing spaced from, and enclosing said jacket, said casing forming an air passage surrounding said smoke passage.

5. In a heater of circulating type, a central combustion chamber having a series of flue gas outlet openings, arranged peripherally near its upper end, an inner jacket extending about said chamber, a top closure member for said chamber adapted to deflect flue gas through said openings into the passage formed by said inner jacket, a vertical flue gas conduit opening into the interior of said inner jacket at the lower end thereof, and an outer jacket surrounding said inner jacket and conduit, said jackets forming a vertical passage therebetween for the flow of circulating air.

6. A stove comprising a combustion chamber having fire-pot and ash receiving portions disposed near its lower end and a series of lateral flue gas discharge openings arranged around its upper portion, a jacket substantially surrounding the combustion chamber and spaced therefrom, said jacket and chamber forming a flue gas conduit therebetween, an imperforate cover forming a closure for the upper end of said combustion chamber, means on the outer surface of said jacket forming a vertical flue, said conduit communicating with said flue through upper and lower openings formed in said jacket, a valve member for said upper opening, and a casing disposed about, and spaced from said jacket, said casing having air inlet and outlet openings in the lower and upper wall portions thereof.
